FOOT ALIGNMENT DEVICE AND METHOD
OF MAKING THE SAME

George Ogden, Worcester, Mass.

Application March 27, 1948, Serial No. 17,464

2 Claims. (Cl. 128—80)

1

This invention relates to a new and improved foot alignment device, and the method of use thereof for the purpose of treating the feet and correcting faulty foot posture.

Another object of the invention resides in the provision of an apparatus comprising a support and a pair of foot plates mounted thereon and separately and independently adjustable so as to determine the degree of faulty posture of the patient due to foot faults; the provision of an apparatus as aforesaid in combination with a measuring level device which is adapted for quick and easy reading of the degree of fault found in the patient's feet, whereby a wedge may be made according to such measurements for insertion in a prescribed shoe to correct the faults of the feet and to maintain such corrections so as to permanently change the structure of the foot for a complete cure.

Another object of the invention is to provide doctors and other medical practitioners with simple and effective means by which they can improve and correct faulty foot posture.

Other objects and advantages of the invention will appear hereinafter.

Reference is to be had to the accompanying drawings in which

Fig. 1 is a view in side elevation illustrating the invention;

Fig. 2 is a top plan view thereof;

Fig. 3 is a view in front elevation;

Fig. 4 is an enlarged view illustrating the foot plate support, part being in section;

Fig. 5 is a view showing the measuring level device;

Fig. 6 is a view illustrating foot postures; and

Fig. 7 is a view illustrating the component parts of the wedge inlay.

A great majority of the foot conditions in this country are overlooked and untreated by the medical profession because there is no practical method or treatment for correction of faulty foot posture. Any work done along these lines involves guess work, extensive mechanical work, and elaborate and usually ineffective preparations, such as cast reproduction.

Casts cannot be said to represent a biological foot under functional conditions. A cast of a foot can only represent one given position, i. e., the position it was taken in. When bare feet in standing position are used as models, rather than casts, such feet can be made to assume any desired position necessary for the purpose of obtaining and maintaining corrected foot posture.

Shoe wedging has long been recognized as the

2

correct approach to the problem but therapeutic value in this method has been nullified because of poor work and poor fitting and because it is necessary to have the work done by unskilled persons who do not have the requisite knowledge of foot anatomy. Of course, the doctor has no control of such a patient since the doctor must depend on outside sources for the work; he does not do it himself. Also, it is well known that the use of wedges has heretofore been made difficult because the patient often refuses to wear shoes with the wedges due to their poor fit and clumsy appearance.

Referring now to the drawings, Fig. 1 shows a cabinet, base or platform generally indicated at 10, which may be made of any suitable material but which is preferably portable and is provided with a relatively strong top element 12. This top element 12 is provided with a pair of slots 14, which extend substantially from end to end of the top element 12 and terminate in enlargements 16.

In each slot there is provided a sliding bolt or the like 18, having a handle 20 and a flange 22, and being in working cooperation with a swivel barrel 24, so as to run the bolt into the barrel and clamp the device in the slot 14 thereby.

The barrel 24 rotates on its axis and contains a ball 26 supporting a standard 28 for universal pivoting movement, as indicated by the dotted lines 30. A handle 32 is threaded or otherwise connected with the barrel 24 so as to clamp the ball 26 in any position desired.

The top of the standard 28 is provided with a platform 34 having a central stud 36 extending upwardly therefrom. This stud 36 projects into an undercut slot 38 in a foot plate 40, there being a bolt 18, foot plate 40, etc., for each foot, as clearly seen in Figs. 2 and 3. The projection 36 extends upwardly into a downwardly opening recess in the bottom of the foot plate 40 at the forepart of the plate. The foot plate is flexible and can be twisted in any direction without breakage and has the general outline 45 of the foot including heel and ball portions.

The foot plate 40 is supported at the heel by means of a standard 42 adjustably clamped in the slot 14 by means of a hand wheel and bolt arrangement 44, similar to that at 20.

The foot plate 40 is provided with an adjustable flange or projection 46 which is capable of forward, horizontal and backward movement is positioned under the heel and the astragalo-scapoid joint and this stabilizes the heel or rearpart of the foot relative to the forepart of

the foot. A heel plate 48 is also provided. A foot plate or guide 50 likewise may be provided for use in certain cases where necessary as, for instance, where a short person or child should have the feet closer together than as permitted by slots 14 in order to assume a normal stance. A hand rail or stand 52 is provided at the front of the support 10 for the convenience and security of the patient as he stands on the foot plates.

An adjustable stop element 65 is mounted on plate 34 to provide a marker for measuring the protrusion of the first metatarsophalangeal joint and also to set the stand to position it directly beneath the ball of the foot.

A measuring and level device generally indicated at 54 is shown in Fig. 5, and this device is shown at its lowermost measuring or zero point at 56, since its bottom surface 58 rests on the top 12. This device comprises a scale 60 and an adjustable plate 62 which measures the distance vertically from the element 56.

In the operation of the device the patient stands on the foot plates and the elements 46 are adjusted to suit the patient, the elements 46 being brought in and to the rear to contact the concave portion of the bottom of the foot at the forward portion of the heel. Thus, for a small foot, the elements 46 are adjusted rearwardly, and for a larger foot, they are adjusted forwardly. Also, the elements 65 are used to locate the first metatarsophalangeal joint, and of course must be longitudinally adjusted to suit, because the distance to the heel varies in substantially all cases. It is, of course, assumed that the foot plates are first level as, for instance, by using the measuring device 54 which is placed on the top surface of the cabinet. Then the entire supporting standard comprising the parts 18, 20, 24, 28, 34, is moved longitudinally in a slot 14 so as to correctly position the support for the front of the foot under the ball. The distance from the heel to the ball of the foot varies with every patient and must be changed with each individual foot.

Now, with the weight equally balanced on the foot plates, the tendo Achillis is observed and if it appears to deviate from a perpendicular in any way, as for instance is illustrated as to one fault in Fig. 6A, it will be seen that the patient may be flat-footed, or have weak arches or some other faulty foot posture of one form or another. In any case, when faulty foot posture is present, the heels of the patient being located against the heel plates 48, as above described, each handle 32 is grasped and because of the universals 26, and the fact that the plates 40 are flexible, the latter may be twisted to any degree within need to level the feet to correct position. The heel portions of plates 40 can rotate to a small degree on a vertical axis, as required by the degree of twisting of the foreparts of plates 40. When additional heel alignment is required, it is possible to obtain this by adjusting element 46 to insure that the body weight will be received in the line of the center of gravity, thus obtaining the desired alignment of the tendo Achillis. In other words, the desired alignment is achieved by governing the heel portion of the foot in accordance with the pre-adjustment of the forward portion of the foot, all as obtained through the use of the device, as above described. By this manipulation of the foot plates and platforms 34, the feet are leveled to a degree where a straight line of the tendo Achillis is observed as at B, Fig. 6. The

first toe is aligned by holding it down by means of an adhesive strap or merely manually or by any other suitable means so that a straight line is obtained from the outside tip of the great toe along the inner border to the ball continuing backward so that it will touch the inner side of the heel. This line is along the inside of the foot from toe to heel. This then determines the degree of correction of "raise" necessary to maintain the feet in the B condition. This position is maintained by tightening the clamps by means of the handle 32 and when the patient steps off the device, the degree of discrepancy is then recorded by using the measuring level device 54. Of course, it is understood that the point at 56 in the measuring device is at a constant so that merely by vertically adjusting the element 62, the degree of discrepancy is easily arrived at and this gives the operator the thickness of wedges necessary to bring about permanent foot alignment. After the measurement is recorded, the foot plates are again leveled.

As shown in Fig. 7, there are a series of wedges labeled .01, .02, etc. These are preferably made of cellulose acetate fabric and are adapted to be made in stock sizes. These wedges are all $\frac{1}{8}$ " thick at their thicker edge and taper off to a feather edge oppositely thereto.

The operator now positions the wedges that he desires to use and assembles them together to build up a thick edge varying in thickness corresponding to the measurements he has made in the measuring device and having an area corresponding to that required in order to obtain the height necessary. The wedges are processed with a lacquer material to cement them together and are now semi-soft and pliable so that the entire assembled device may be pressed against the patient's foot while the foot is extended and the patient seated on a chair. Handpressure is used to partially mold and shape the assembled wedges to the foot and to accommodate for abnormal bony prominences or deformities.

After such molding and shaping, the assembled wedges are placed on the foot plates and while still pliable the patient is asked to stand on them. Care must be taken to keep the molds in place while the patient is in position. The operator uses his fingers to keep the wedges in proper position and with both feet on the foot plates the patient is asked to equalize the pressure so that he is standing equally on each foot. The patient is to stand on both feet for two minutes during which period additional wedges may be placed if necessary. The wedges now place the tendo Achillis in a straight line as at B with the foot plates on a level. The patient may then step off the foot plates and the assembled wedges are cut to shape to fit a shoe previously prescribed. The wedges are placed in the shoes and the patient is allowed to stand on them for a minute. After walking for two hours, the appliance is rigid enough to hold the adjustments made to obtain constant foot alignment.

The appliance may be completed in the following manner: The top surface of the appliance is painted with lacquer and the rough surface of the leather is painted with lacquer, then these two wet surfaces are placed together and pressed against the patient's foot to adhere and to smooth out wrinkles in the leather. The inlay is placed in the shoe again. Patient is allowed to stand one minute after which the appliances may be worn indefinitely. This operation is advisable to be

completed on second visit although it can be completed immediately as explained.

It is to be understood that the tilt required for correct posture will be in whatever direction is necessary to accomplish the purpose. Hence, if an arch is too high, the tilting will be in a direction opposite to that described.

Having thus described my invention and the advantages thereof, I do not wish to be limited to the details herein disclosed otherwise than as set forth in the claims, but what I claim is:

1. Device of the class described comprising a support, an upright and a spaced universal joint thereon, a flexible foot plate having a heel portion on the upright and a ball portion on the joint, and means to adjust the universal joint to twist the foot plate at the ball portion relative to the heel portion thereof to determine correct foot alignment of the patient.

2. Foot alignment appliance comprising a support, a generally rigid, upright thereon, an angularly tiltable upright on the support in spaced

relation to first named upright, a flexible foot plate having a heel portion and a ball and toe portion on the uprights, the heel portion being located on the first named upright and the ball and toe portion on the tiltable upright, and means to tilt the latter so that the foot plate twists sufficiently to determine correct foot alignment of the patient.
